ROBERT C. MATHES, OF WYOMING, NEW JERSEY, ASSIGNOR TO WESTERN ELECTRIC COMPANY, INCORPORATED, OF NEW YORK, N. Y., A CORPORATION OF NEW YORK.

OPERATING RELAY.

Application filed July 25, 1923. Serial No. 653,624.

This invention relates to relay operation and to repeating current waves, and has for an object to render a relay selectively responsive to opposite directions of alternating current energy flow in a circuit, and to control the pointing of a repeater in a line.

In accordance with the invention a relay may be rendered selectively responsive to opposite directions of energy flow in a line by a network, preferably a network of reactances connected to the line and controlling the relay.

In the form of the invention described herein, the reactances of the network are 15 transformer windings, with four circuits taken therefrom, two of the circuits leading to the two line sections at opposite sides of the relay, respectively, and the other two circuits taking off from the transformer 20 windings two currents which are made to control the relay differentially. The transformer windings are preferably so related that these four circuits are biconjugate when they present the proper impedances to the transformer windings. For example, the 25 transformer windings may be related as in any one of many well known types of so-called hybrid coil connections employed for uniting a two-wire signalling circuit and its 30 artificial line with a four-wire signaling circuit in such manner as to render the two-wire circuit and the artificial line conjugate and to also render the input and the output branches of the four-wire circuit conjugate. 35 In such a two-wire to four-wire connection the two-wire circuit and the receiving branch of the four-wire circuit (that is, the branch which transmits to the two-wire circuit) may be regarded as corresponding to the 40 two line sections at opposite sides of the relay to be selectively operated as mentioned above, in the system of this invention; and the artificial line and the transmitting branch of the two-wire to four-wire connection 45 may be regarded as corresponding to the remaining two circuits taken off from the reactance network, mentioned above, of the system of this invention—that is, the two 50 circuits which take off from that network currents that are made to differentially control the relay which is to be selectively operated in accordance with the direction of energy flow in the line to which it is connected. Which of the differentially active cur-

rents is the greater depends only upon the direction of flow of energy in the line, so that the resultant control action of the differentially acting currents upon the relay may readily be made to cause the relay to be selectively responsive to the direction of energy flow in the line.

In the system of this invention the reactance network referred to above for connecting the above mentioned biconjugate circuits should preferably present to each of those 65 circuits an impedance approximately equal to the impedance of that one of those circuits, so that the network will be a so-called maximum output network. Such networks have been treated by Campbell and Foster 70 in their article entitled "Maximum output networks for telephone substations and repeater circuits," published in the transactions of the American Institute of Electrical Engineers, 1920, Vol. 39, Part 1, pages 231 to 75 290.

In an application of the invention to the reversal of the pointing of a telephone repeater, the relay made selectively responsive to the direction of energy flow in the line by 80 a network such as is referred to above controls the reversal of the pointing of the repeater in the line, and preferably (in the general fashion disclosed in the application of W. S. Gorton, Serial No. 635,865, May 85 1, 1923, "operating relays") the position of the repeater in the line is so changed when the repeater is reversed that the network is always on the output side of the repeater so 90 that it can be reached by transmission approaching the repeater from either line.

In the accompanying drawings Fig. 1 shows a circuit wherein a three-winding transformer is connected to a line and renders a relay selectively responsive to opposite directions of alternating current energy flow in the line; Fig. 2 shows an application of the invention to the reversal of the pointing of a telephone repeater; and Fig. 3 shows diagrammatically the arrangement 100 of coils on transformers employed in the system of Fig. 2.

In Fig. 1, a hybrid coil T, having a balancing network Z_2 and a bridge circuit Z_3 , connects a line P to a line Q, for transmitting alternating currents, for instance telephonic currents, from each line to the other. The hybrid coil is shown as a three-winding

- transformer with a winding or limb T_p in line P , a winding or limb T_q in line Q , and a winding or limb T_2 in the circuit of the network Z_2 . The impedance of the balancing network Z_2 includes the impedance of the input circuit of an amplifier-rectifier 16, so that an electro-motive force across this impedance Z_2 acts through the amplifier-rectifier 16 to cause direct current to flow in the lower winding of a polarized relay 15. The impedance of the bridge circuit Z_3 includes the impedance of the input circuit of an amplifier-rectifier 14, and an electro-motive force across this impedance Z_3 acts through the amplifier-rectifier 14 to cause direct current to flow in the upper winding of the polarized relay. These direct currents flow through the windings of the relay in opposite directions with respect to the magnetic circuit of the relay. Thus the armature of the relay is drawn one way or the other depending upon the relative magnitudes of the energies producing the electromotive forces just mentioned. The amplifier-rectifiers are preferably electron tube devices, of the character described hereinafter in more detail in connection with Fig. 2.

It will now be shown that for energy flowing from line Q to line P the energy due to the voltage E_3 across impedance Z_3 is greater than the energy due to the voltage E_2 across impedance Z_2 and for energy flowing from line P to line Q the energy due to voltage E_2 is greater than the energy due to voltage E_3 . For simplicity in working out the circuit equations consider the balanced repeating coil to be made up with one to one windings each of total inductance $4L$. Then each of the balanced windings will have an inductance L . The transformer will be con-

sidered to have no leakage, no iron losses and no D. C. resistance in its windings, but to be of finite inductance.

Let subscripts 1 denote impedance and current of line Q , 2 denote network impedance and current, 3 those of the bridge, and 4 those of line P , and consider an E. M. F. to be inserted in line Q . The convention in regard to the windings shown on Fig. 1 is that when currents are flowing in the directions shown by the arrows, magnetism in the core is produced by each in the same direction. We then have

$$I_1 = I_2 + I_3 \quad (1)$$

$$E_1 = Z_1 I_1 + j p L I_1 + j p L I_2 + 2 j p L I_4 + Z_3 I_3 \quad (2)$$

$$O = Z_2 I_2 + j p L I_1 + j p L I_2 + 2 j p L I_4 - Z_3 I_3 \quad (3)$$

$$O = a j p L I_1 + 2 j p L I_2 + 4 j p L I_4 + Z_4 I_4, \quad (4)$$

where $p = 2\pi f$, f being the frequency in cycles per second.

From (2) and (3)

$$E_1 = Z_1 I_1 - Z_2 I_2 + 2 Z_3 I_3$$

Combining this with (1)

$$E_1 = (Z_1 - Z_2) I_2 + (2 Z_3 + Z_1) I_3.$$

Whence

$$I_3 = \frac{E_1}{2 Z_3 + Z_1} - \frac{(Z_1 - Z_2)}{2 Z_3 + Z_1} I_2 \quad (5)$$

From (3) and (4)

$$O = 2 Z_2 I_2 - 2 Z_3 I_3 - Z_4 I_4 = (2 Z_2 + Z_4) I_2 - (2 Z_3 - 1/2 Z_4) I_3. \quad (6)$$

Whence

$$I_2 = \frac{2 Z_3 - \frac{1}{2} Z_4}{2 Z_2 + Z_4} I_3. \quad (7)$$

From (7)

$$\frac{Z_3 I_3}{Z_2 I_2} = \frac{\text{voltage drop across } Z_3}{\text{voltage drop across } Z_2} = \frac{2 Z_2 Z_3 + Z_3 Z_4}{2 Z_2 Z_3 - \frac{1}{2} Z_2 Z_4} \quad (7a)$$

Now considering the case where a source of E. M. F. is inserted in line P , and using the same circuit constants and subscripts but small letters for the currents, we have,

$$i_1 = i_2 + i_3 \quad (10)$$

$$E_4 = 2 j p L i_1 + 2 j p L i_2 + 4 j p L i_4 + Z_4 i_4, \quad (11)$$

$$O = Z_1 i_1 + j p L i_1 + j p L i_2 + 2 j p L i_4 + Z_3 i_3 \quad (12)$$

$$O = Z_2 i_2 + j p L i_1 + j p L i_2 + 2 j p L i_4 - Z_3 i_3. \quad (13)$$

From (12) and (13)

$$O = Z_1 i_1 - Z_2 i_2 + 2 Z_3 i_3.$$

Combining this with (10) we get

$$\frac{Z_3 i_3}{Z_2 i_2} = \frac{\text{voltage drop in } Z_2}{\text{voltage drop in } Z_3} = \frac{2 Z_2 Z_3 + Z_1 Z_2}{2 Z_2 Z_3 - Z_1 Z_3} \quad (15a)$$

If windings T_q and T_2 are equal, then with an E. M. F. inserted in line P no current will flow in impedance Z_3 when Z_1 equals Z_2 , the energy which the E. M. F.

$$i_1 = \frac{2 Z_3 + Z_2}{Z_2 - Z_1} i_3 \text{ or } i_3 = \frac{Z_2 - Z_1}{2 Z_3 + Z_2} i_1. \quad (14)$$

And

$$i_2 = \frac{2 Z_3 + Z_1}{Z_2 - Z_1} i_3. \quad (15)$$

Also

$$\frac{i_1}{i_2} = \frac{2 Z_3 + Z_2}{2 Z_3 + Z_1}. \quad (16)$$

From (15)

supplies to the transformer dividing equally between the two impedances Z_1 and Z_2 under these conditions.

If windings T_q and T_2 are equal, then

with an E. M. F. inserted in line Q no current will flow through Z_2 when Z_4 equals Z_3 multiplied by the impedance ratio of T_P to T_2 , the energy which the E. M. F. supplies to the transformer dividing equally between Z_3 and Z_4 under these conditions.

It is not necessary to have an equal division of energy between Z_1 and Z_2 for transmission from line P to line Q, or an equal division of energy between Z_3 and Z_4 for transmission from line Q to line P, in order to have the current in one of the windings of relay 15 zero in either case. For example, if in transmitting from line P to line Q it is desired to have three quarters of the voltage or the energy supplied by Z_4 go to Z_2 and only one quarter go to Z_1 , impedance Z_2 may be made three times as great as Z_1 , and winding T_2 may be given three times as many turns as winding T_Q ; and if it is further desired, in transmitting from line Q to line P, to have three quarters of the energy or the voltage supplied by Z_1 go to Z_3 and only one quarter go to Z_4 , impedance Z_3 multiplied by the impedance ratio of T_P to T_2 may be made three times as great as Z_4 , winding T_2 being given three times as many turns as winding T_Q . Thus, by proportioning the windings of the hybrid coil and the impedances connected thereto, the ratio of the energies transmitted by the hybrid coil to the line and to the active winding of relay 15 may be varied, for each direction of transmission in lines P and Q.

70 Consider the line and network to be well balanced, that is, $Z_1 = Z_2 = Z$. Then equation (5) reduces to

$$I_3 = \frac{E_1}{2Z_3 + Z_2} \quad (20)$$

75 and (19) to

$$i_1 = \frac{-E_4}{Z_4 + 2Z} \quad (21)$$

80 These are both of the same general form and may be differentiated for maximum power into impedances Z_3 and Z respectively. Considering the impedances Z_3 and Z as resistances, the power may be written thus

$$\text{Power} = I_3^2 Z_3$$

85 Substituting for I_3 its value in equation (20), we have

$$90 \quad \text{Power} = \frac{E_1^2 Z_3}{(2Z_3 + Z)^2}$$

95 Taking the derivative of power with respect to Z_3 , we have

Preferably, where winding T_Q and T_2 are to have the same number of turns, the relation

$$2Z_3 = \frac{1}{2} Z_4 = Z_2 = Z_1 \quad 40$$

should obtain, for then, as will now be explained, the network connecting these impedances will not only be doubly conjugate but will further be a maximum output network, so that, for each direction of transmission in lines P and Q, the energy transmitted to the network will be the maximum possible value. By adding (12) and (13) and combining with (16) we can get

$$i_1 = \frac{-4jpL}{(Z_1 + 2jpL) + \frac{(2Z_3 + Z_1)}{(2Z_3 + Z_2)} (Z_2 + 2jpL)} \quad 55$$

If we now assume that Z_1 and Z_3 are small compared to $2jpL$ (a condition met by well designed transformers) we get approximately

$$i_1 = -\frac{2}{1 + \frac{2Z_3 + Z_1}{2Z_3 + Z_2}} \quad (17)$$

Subtracting twice (12) from (11) we get

$$E_4 = Z_4 i_4 - 2Z_1 i_1 - 2Z_3 i_3 \quad (18)$$

Substituting in (18) the values of i_4 and i_3 from (17) and (14) in terms of i_1 we get this solution for i_1

$$i_1 = \frac{-E_4}{\frac{1}{2} \left(1 + \frac{2Z_3 + Z_1}{2Z_3 + Z_2} \right) Z_4 + 2Z_1 + 2Z_3 \left(\frac{Z_2 - Z_1}{2Z_3 + Z_2} \right)} \quad (19)$$

$$\frac{(2Z_3 + Z)^2 - 4Z_3(2Z_3 + Z)}{(2Z_3 + Z)^4}$$

95 On setting this expression equal to zero for maximum power and solving, we have

$$Z_3 = \frac{Z}{2}$$

Treating the equation (21) in a similar manner and differentiating from maximum power, we obtain

$$Z_4 = 2Z$$

These two conditions taken together give us the relation

$$2Z_3 = \frac{1}{2} Z_4$$

When the network is designed for a maximum output network to meet these ideal impedance conditions, that is,

$$Z_1 = Z_2 = 2Z_3 = \frac{1}{2} Z_4$$

it follows that the proper directional oper-

ation of the circuit will be maintained even if one of the balancing impedances is far from normal. For instance, equation 7A shows that if

5

$$\frac{1}{2} Z_4 = 2 Z_3$$

we have an infinite margin of operation. But it also follows that if Z_4 were so widely

10 off of normal as to be zero or infinite the ratio of energies in Z_3 to that in Z_2 will be 2 to 1. Also if in equation 15A the impedance Z_1 is made zero or infinite the energy in Z_2 is twice the energy in Z_3 and we will 15 have a safe margin of operation in the desired direction. Thus even if the outgoing line to which the repeater is connected has a very irregular impedance the circuit will function satisfactorily.

20 In Fig. 2 a repeater 17 comprising a repeating element 18, an input transformer 20 and potentiometer 21, and an output transformer 22, is reversibly connected to repeat from line Q to line P and from line P to line Q, the reversing being accomplished by a relay means or reversing switch 23. This 25 reversing switch comprises four relays 24, 25, 26 and 27, which may be polar relays having armatures mechanically connected as 30 indicated by bar 28.

The windings of each of the relays 24, 25, 35 26 and 27 of Fig. 2 are controlled in the same general manner as the windings of relay 15 of Fig. 1, but in Fig. 2 there is employed, instead of the transformer T of Fig. 1, a transformer arrangement X which 40 comprises two three-winding transformers, each of which has upon its core four coils which are wound in the same direction, as shown in Fig. 3. One terminal of each coil has been given an odd number and the other the next higher even number. The coils have been wound in such a direction that when current flows from an odd to an even 45 terminal the flux set up in the core is in a given direction irrespective of which coil is taken. The same would be true if current were to flow from an even numbered to an odd numbered terminal, but in this case the flux would of course be in the opposite direction.

50 As stated, the transformer arrangement X consists of two transformers, each comprising four coils. The coils of these transformers are connected in groups A, B, C, and D, of two each, these groups being associated with the various circuits connected to the transformer arrangement. Thus the group A is connected with an impedance Z_1 which corresponds to the impedance Z_1 of Fig. 1, the group B is connected with an impedance Z_2 which corresponds to the impedance Z_2 of Fig. 1, the group C is connected with an impedance Z_3 corresponding to Z_3 of Fig. 1, and the group D is connected with an impedance

Z_4 corresponding to the impedance Z_4 of Fig. 1. The coil 1-2 of group A, together with the coils 3-4, 7-8 of group D and coil 5-6 of group B constitute one of the transformers of the transformer arrangement X, 70 and in like manner coil 5-6 of group A, coils 3-4, 7-8 of group C and coil 1-2 of group B constitute the other transformer of the transformer arrangement. Since all of the groups are symmetrical, and the corresponding elements of each group have the same values, a balanced condition exists between the four circuits related to each other by the said transformer arrangement. Let it be assumed that energy is being transmitted from impedance Z_1 into the transformer arrangement X, and furthermore let the direction of flow of current at any instant in group A be as indicated by the solid arrows. The current flowing in coil 85 1-2 of group A will induce a potential in the coils of group D that will cause flow of current from 4 to 7 and will also induce a potential in coil 6-5 of group B that will tend to cause a flow of current from 6 to 5. 90 Similarly, the flow of current through coil 5-6 of group A, as indicated by the solid arrow, will induce a potential in the coils of group C that will cause flow of current from 4 to 7, and there will also be induced in coils 95 2-1 of group B a potential that will tend to cause current to flow in the direction indicated by the solid arrow. If the impedance Z_4 equal the impedance Z_3 , equal currents 100 will exist in the coil groups D and C connected to these impedances, and as a result the potentials induced in the two coils of group B are equal in magnitude. It will be seen, therefore, that no resultant current flows in the circuit of coil group B and impedance Z_2 . The current set up in group D will be transmitted in the direction of the arrows and will be fed into impedance Z_4 . The current set up in group C will be transmitted to the input circuit of the amplifier-rectifier 14, which corresponds to the amplifier-rectifier 14 of Fig. 1.

If, on the other hand, it is assumed that a signaling wave is being transmitted from impedance Z_4 into the transformer arrangement X, the distribution of energy in the said arrangement is as follows: The direction of flow of current of the transmitted wave in the group D is represented, for example, by the dotted arrows, viz., the current will flow through the coils of the said group in the direction from 7 to 4. This flow of current will induce potentials in groups A and B, which are related to group D by having one of their coils upon the 125 same core. The potentials induced in coils 6-5 and 2-1 of groups A and B respectively will cause current to flow in the directions indicated by the dotted arrows. Since the circuits of groups A and B are 130

closed, current will flow in coils 2-1 and 6-5 of group A, and in coils 6-5 and 1-2 of group B in the directions indicated by the dotted arrows. If the impedance Z_2 equals the impedance Z_1 these currents will be of equal magnitude. In view of the fact that coils 1-2 and 6-5 of groups A and B respectively are upon the same magnetic core, and since the flow of current in coil 1-2 of group B is in opposite direction to the flow of current in coil 6-5 of group A (as may be clearly seen by considering the distribution of coils shown in Fig. 3), no resultant flux occurs in the core, and consequently no induced potential results in the windings of group C. Consequently the energy of the transmitted signaling wave, which is impressed upon group D from impedance Z_4 is in turn impressed upon impedances Z_1 and Z_2 , but is not impressed upon Z_3 . The impedance Z_2 includes a transformer t and the input circuit of an amplifier-rectifier 16 which corresponds to the amplifier-rectifier 16 of Fig. 1.

The amplifier-rectifier 16 comprises an amplifying tube 40 and an amplifying and rectifying tube 41. The amplifier-rectifier 14 comprises an amplifying tube 43 and an amplifying and rectifying tube 44. The amplifier-rectifier 16 in Fig. 2 feeds the left-hand windings of each of the relays 24, 25, 26 and 27 through leads 45 and 46, just as the amplifier-rectifier 16 of Fig. 1 feeds the lower winding of relay 15 of Fig. 1; and the amplifier-rectifier 14 in Fig. 2 feeds the right-hand windings of each of the relays 24, 25, 26 and 27 through leads 47 and 48, just as the amplifier-rectifier 14 of Fig. 1 feeds the upper winding of relay 15. In each of the relays 24, 25, 26 and 27, as in the relay 15, the two windings of the relay act oppositely upon the magnetic circuit of the relay.

When the switch 23 is in the position shown, the relay 24 connects line Q to feed potentiometer 21, through the circuit from the upper end of the right-hand winding of a transformer t_1 , armature of relay 24, leads 29 and 30, potentiometer 21, and leads 31 and 32 to the lower end of the right-hand winding of transformer t_1 . Also, with the switch 23 in the position shown, the relay 25 connects the output transformer 22 to feed line P through transformer arrangement X, a transformer t_3 , contacts of relays 26 and 27, and a transformer t_2 , the input circuit to transformer arrangement X being from the upper terminal of the secondary winding of transformer 22 through lead 34, armature of relay 25, lead 35, coil group A, and lead 32 to the lower end of the secondary winding of transformer 22. The circuit through which the transformer arrangement X feeds transformer t_3 extends from coil group D to the left-hand winding of transformer t_3 . The circuit through

which transformer t_3 feeds transformer t_2 extends from the upper terminal of the right-hand winding of transformer t_3 , through lead 36, armature of relay 26, lead 37, armature of relay 27, to the upper end of the left-hand winding of transformer t_2 , and from the lower end of the left-hand winding of transformer t_2 to the lower end of the right-hand winding of transformer t_3 .

When the reversing switch is operated, in the manner described hereinafter, to the position alternative to that in which it has been shown, the line P is connected to feed potentiometer 21 through the transformer t_2 , the armature and right-hand contact of relay 27, lead 30, potentiometer 21, and leads 31 and 32; and at the same time, the relay 26 connects the output transformer 22 to feed line Q through transformer t_3 , the transformer arrangement X, contacts of relays 25 and 24, and transformer t_1 . The circuit through which transformer 22 feeds transformer t_3 extends from the upper end of the secondary winding of transformer 22, through lead 34, armature of relay 26, lead 36, right hand winding of transformer t_3 , and lead 32 to the lower end of the secondary winding of transformer 22. The circuit through which transformer t_3 feeds the transformer arrangement X extends from the left-hand winding of transformer t_3 through the coil group D. The circuit through which the transformer t_1 extends from coil group A through lead 35, armature of relay 25, lead 38, armature of relay 24, and left-hand winding of transformer t_1 back to coil group A.

It will be noted that when the reversing switch 23 operates from the position shown to the alternate position, it not only reverses the pointing of the repeater between lines Q and P, but also changes the position of the repeater 17 in the line, from its position between line Q and transformer arrangement X to a position between line P and transformer arrangement X. Similarly, when the reversing switch 23 operates to the position in which it is shown, the repeater is shifted from a position between line P and transformer arrangement X to a connection between line Q and transformer arrangement X.

The operation of the system shown in Fig. 2 will now be apparent. With switch 23 in the position shown, the system is set for repeating from line Q to line P, the input and output circuits of the repeater being as traced above. The system remains in this condition until transmission approaches the repeater output over line P; for when energy approaches the input of the repeater over line Q and is amplified and transmitted to line P, the voltage applied to Z_3 will be greater than that applied to Z_2 , as explained above, so that coil group C will cause am-

plifier-rectifier 14 to feed to the right-hand winding of each of relays 24, 25, 26 and 27 a current greater than that which coil group B causes amplifier-rectifier 16 to feed to the 5 left-hand winding of each of the relays 24, 25, 26 and 27.

When transmission approaches the repeater output from line P, the switch 23 being in the position shown, transformer t_2 10 supplies current to transformer t_3 through the armatures of switches 27 and 26, and the transformer t_3 delivers energy to coil group D of transformer arrangement X. Therefore the voltage applied to Z_2 will be greater 15 than that applied to Z_3 , as explained above, so that coil group B will cause amplifier-rectifier 16 to feed to the left-hand winding of each of relays 24, 25, 26, and 27 a current greater than that which coil group C causes 20 amplifier-rectifier 14 to feed to the right-hand winding of each of the relays 24, 25, 26 and 27. These switching relays therefore reverse, causing the pointing of the repeater to be reversed and the position of 25 the repeater in the line to be changed as explained above. The direction of flow of the transmission through the transformer arrangement X is the same after the accomplishment of the reversal of the repeater as 30 when the reversal of the repeater was initiated; and therefore the amplified transmission from line P to line Q tends to hold the repeater pointed toward line Q. The repeater remains pointed toward line Q until 35 transmission approaches its output from line Q, whereupon the pointing of the repeater and the position of the repeater in the line are again changed. As a result of the changing of the position of the repeater in 40 the line at each reversal of the repeater, the transformer arrangement X is always in the line at the output side of the repeater so that it can be reached by transmission approaching the repeater from either line.

45 For a given adjustment the means shown in Fig. 2 for rendering the relay devices selectively responsive to opposite directions of energy flow in the lines will operate best when employed on lines having impedances within certain limits, as in the case of the corresponding means of Fig. 1. In Fig. 2, as was noted in connection with Fig. 1, for lines having the proper impedance the current in one of the impedances Z_2 and Z_3 is zero and the current in the other one of these two impedances has a finite magnitude, these two impedances and the two lines P and Q constituting a biconjugate network, with the impedance Z_2 conjugate to one of the lines, and the impedance Z_3 conjugate to the other line. As indicated above, the impedance relations between these four parts of the biconjugate network, of either Fig. 1 or Fig. 2 may be regarded as corresponding 60 to those between the line, balancing network,

repeater output branch and repeater input branch of the maximum output hybrid coil connection commonly employed in 22-type repeaters such as described in an article by Gherardi and Jewett published in the 70 "Transactions of the American Institute of Electrical Engineers" for 1919, Vol. XXXVIII, Part II, page 1287. In such a hybrid coil connection the line and the repeater output branch may be regarded as 75 corresponding to the two line sections of the repeater circuit of this invention, and the balancing network and the repeater input branch of the 22-type repeater circuit may be regarded as corresponding to the impedances of the input circuits of the amplifier-rectifiers of the circuit of this invention. In the circuits of this invention, the network connecting the two line sections and the input circuits of the amplifier-rectifiers should 80 preferably present to each one of said line sections and input circuits an impedance approximately equal to the impedance of each such one of the two line sections or input circuits, so that the network will be a 90 maximum output network. However, the means of Fig. 2 for rendering the relay devices selectively responsive to oppositely directed transmission will work directionally regardless of the impedances of the lines into 95 which it works, as was the case with the corresponding means of Fig. 1.

It should be understood that the invention is capable of embodiment in forms and arrangements other than those shown, without departing from the spirit and scope of the appended claims.

The invention claimed is:

1. The combination with a two-way transmission circuit comprising two sections, of a 105 relay, two circuits for controlling said relay, and means comprising a plurality of coupled reactances for associating said sections with each other and with said relay controlling circuits, said reactances being proportioned with respect to the impedances of said sections and said relay controlling circuits so that energy transmitted over said transmission circuit in one direction will control said relay in one sense and energy transmitted over said transmission circuit in the opposite direction will control said relay in another sense.

2. A circuit for transmitting alternating current energy in opposite directions, a relay having an armature, and means whereby said relay is caused to operate its armature in opposite directions in accordance with the direction of transmission of the alternating current energy in said circuit, said means comprising a three winding transformer having two of its windings in said circuit and having its third winding in inductive relation with said relay.

3. A two-way transmission circuit, a po- 130

larized relay having an armature and windings, and means whereby said relay is caused to operate its armature in opposite directions in accordance with the direction of transmission in said circuit, said means comprising a three-winding transformer, connected to said circuit and to said relay windings.

4. A circuit for transmitting alternating current energy in opposite directions, a relay armature, and means for operating said relay armature in opposite directions in accordance with said opposite directions of said energy transmission in said circuit, said means comprising means for deriving alternating current energies from different parts of said circuit, combining said derived energies and controlling said relay armature in accordance with the resultant effect, said last mentioned means comprising a three-winding transformer connected to said circuit.

5. A circuit for transmitting alternating current energy in opposite directions, a unidirectional current transmitting device connected therein, means comprising a relay armature for controlling the transmitting efficiency of said device in a given direction, and means for operating said armature in opposite directions in accordance with said opposite directions of said energy flow in said circuit, said second mentioned means comprising means for deriving alternating current energies from different parts of said circuit, balancing said derived energies against each other and controlling said relay armature in accordance with the resultant effect, and said last mentioned means comprising a three-winding transformer connected to said circuit.

6. A circuit for transmitting alternating current energy in opposite directions, a unidirectional current transmitting device connected therein, means comprising a relay armature for controlling the transmitting efficiency of said device in a given direction, and means for operating said armature in opposite directions in accordance with said opposite directions of said energy flow in said circuit, said second mentioned means comprising stationary means for deriving alternating current energies from different parts of said circuit, balancing said derived energies against each other and controlling said relay armature in accordance with the resultant effect, and said last mentioned means comprising a three-winding transformer connected to said circuit.

7. A circuit for transmitting alternating current energy in opposite directions, a unidirectional current transmitting device, switching means for connecting said device to said circuit, means comprising a relay armature for controlling said switching means, and means for operating said armature in opposite directions in accordance with the direction of transmission in said circuit, said means comprising means for deriving alternating current energies from different parts of said circuit, combining said derived energies and controlling said relay armature in accordance with the resultant effect, and said last mentioned means comprising a three-winding transformer connected to said circuit.

8. A line, a unidirectional current transmitting device connected therein, means for distinguishing between opposite directions of electrical energy transmission in said line, and means controlled by said first-mentioned means for controlling the pointing of said device, said first mentioned means comprising a three-winding transformer connected to said line and to said second mentioned means.

9. A line for transmitting alternating current energy in opposite directions, a repeater adapted to be connected therein, a relay comprising an armature, stationary means for causing said relay to tend to operate its armature in opposite directions in accordance with the direction of alternating current energy transmission in said line, and means controlled by said relay for controlling the connection of said repeater in said line, said stationary means including a three-winding transformer connected to said line and also including means connecting said three-winding transformer to said relay.

10. In combination, a circuit, two impedances, means comprising a three-winding transformer so connecting said impedances to said circuit that the ratio of the electromotive forces across said impedances due to one direction of energy flow in said circuit is greater than the correspondingly taken ratio of the electromotive forces across said impedances due to the opposite direction of energy flow in said circuit, and two differentially acting relay windings connected across said two impedances, respectively.

11. In combination, a circuit, a switch device, and means for rendering said switch device selectively responsive to opposite directions of energy flow in said circuit, said means comprising a network having branches conjugate respectively to two parts of said circuit, and said network comprising a three-winding transformer which has two of its windings connected in said two parts, respectively, of said circuit and has its third winding connected in circuit with one of said branches.

12. In combination, a line comprising two sections, a relay device, and means for rendering said device selectively responsive to opposite directions of energy flow in said line, said means comprising two impedances and a network so connecting said two im-

- pedances and said two line sections as to present to each of said line sections and impedances an impedance approximately equal to the impedance of that one of said two line sections or said two impedances, and said network comprising a three-winding transformer having two of its windings in circuit with said two line sections, respectively, and having its third winding in circuit with one of said two impedances. 10
13. In combination with a line having two sections, a directional circuit, said directional circuit comprising two relay circuits and transformer windings for connecting one of said relay circuits substantially in conjugate relation with one of said line sections, and the other of said relay circuits 15
- substantially in conjugate relation with the other of said line sections, and differential means controlled by said relay circuits. 20
14. In combination with a line having two sections, a directional circuit, said directional circuit comprising two relay circuits and two three-winding transformers for connecting one of said relay circuits substantially in conjugate relation to one of said line sections and the other of said relay circuits substantially in conjugate relation to the other of said line sections, and differential means controlled by said relay circuits. 25

In witness whereof, I hereunto subscribe my name this 19th day of July A. D., 1923.

ROBERT C. MATHES.
